WHEELED JACK FOR CONTAINERIZED FREIGHT

Henry Beitscher, 6620 N. 18th St., Philadelphia, Pa.

Filed Mar. 5, 1963, Ser. No. 73,825

Term of patent 14 years

(Cl. D14—3)

Fig. 2

Fig. 1

Fig. 3

Fig. 4

FIGURE 1 is a side elevational view of a wheeled jack for containerized freight showing my new design;

FIGURE 2 is a top plan view thereof;

FIGURE 3 is a front elevational view thereof; and

FIGURE 4 is a rear elevational view thereof.

I claim:

The ornamental design for a wheeled jack for containerized freight substantially as shown.
